UNITED STATES PATENT OFFICE.

JOHN UMSTÄTTER, OF NEW YORK, N. Y.

CURTAIN-HANGER.

1,056,384.

Specification of Letters Patent. Patented Mar. 18, 1913.

Application filed December 12, 1911. Serial No. 665,355.

To all whom it may concern:

Be it known that I, JOHN UMSTÄTTER, a citizen of the United States, and a resident of New York, county and State of New York, have invented a certain new and useful Improvement in Curtain-Hangers, of which the following is a full, clear, and exact specification.

This invention relates more particularly to a class of devices adapted to be used for hanging draperies.

My invention has for its object primarily to provide a form of hanger or device designed to be employed for suspending draperies or the like from poles supported at the windows, doors, and other places of a building, and wherein is employed a supporting plate or member having one or a plurality of pins or gripping members by which the drapery is removably attached to the supporting plate and which is held against displacement by a spring member or catch. The catch may be operated by a locking element or clamp, and the draperies when evenly arranged may then be readily applied upon a suitable pole or rod by a hook provided upon the supporting plate.

Another object of the invention is to also provide upon the supporting member or plate one or a plurality of hanging elements or pins whereby the folds of the curtains or the like may be attractively and conveniently draped thereon; and a further object of the invention is to provide a form of curtain hanger of a simple, inexpensive and efficient construction and which is susceptible of being made in various sizes.

Still further objects of the invention are to provide a hanger for curtains in the form of a hook which may be readily applied to a curtain pole of ordinary construction; also to provide a hanger that may be applied or may be readily removed without the aid of mechanical tools or without altering or especially adapting the pole to this particular device; and to provide a hanger which may be if desired produced wholly of sheet material or metal by the use of dies and stamping machinery.

A practical embodiment of the invention is represented in the accompanying drawing forming a part of this specification in which similar characters of reference indicate corresponding parts in all the views, the said invention being more fully described here-

inafter and then pointed out in the appended claims.

In the drawing, Figure 1 is a perspective view of one form of curtain hanger embodying my invention as applied upon a pole. 60 Fig. 2 is a front elevation of the curtain hanger, and Fig. 3 is a rear elevation thereof.

The device or curtain hanger 10 has a supporting member or plate 11 which may be integrally formed with, or made separately and joined to one end of a hook 12 having its opposite end spaced from said supporting plate so that the hook may be readily guided over a pole or rod, as shown 70 at 13, when drapery is applied to the hanger, as will be hereinafter more fully described.

The supporting member or plate 11 may be of any desired shape and size, but is preferably in the form of an elongated strip, and adjacent to the free end thereof is provided one or a plurality of pins or gripping members 14 which extend at an angle with respect to one surface of said supporting plate. The drapery after being folded in a suitable 80 way may then be removably fastened upon the pins or gripping members 14, and for the purpose of holding the drapery against displacement upon said pin, I provide a spring plate or clamping member, as 15. 85

The spring plate or clamping member 15 is somewhat similar in shape to the supporting plate 11, and to lessen the cost of manufacture of my curtain hanger, I prefer to stamp or die-out a portion of the central 90 part of the material of the hook 12 to form said clamping member. When the device is made of spring metal the clamping member 15 is curved, as at 16, and is then guided so as to be in substantially spaced parallel 95 arrangement with the supporting plate 11, in order to permit engagement of the free end of said clamping member with the free end of the supporting plate. Adjacent to the free end of the clamping member 15 and in register with the pins 14 of the supporting plate 11 are provided openings 17 for said pins to be guided therethrough to hold the drapery against displacement when applied thereon, and serving as a means to 100 hold the clamping member and supporting plate together, a locking element, as 18, is provided.

The locking element 18 consists of a lever or handle 19 having two oppositely dis- 110

posed pins 20 and 21 which are movably guided through eyes 22 and 23 provided in lugs 24 and 25 formed upon the opposite edges of the supporting plate 11. Upon the 5 lever or handle 19 and in alinement with the pins 20 and 21 is a finger or lug 26 which is disposed so as to be adapted to engage the clamping member 15 for forcing it toward and upon the supporting plate 11 when the 10 lever is swung from the surface of said clamping member. The clamping member 15 and the supporting plate 11 will then be held in locked engagement, and to unlock the parts for removing the drapery from 15 the pins 14 the lever or handle 19 is swung in a reverse direction and into contact with the clamping member 15 and the finger or lug 26 will be freed from engagement with the clamping member.

20 Serving to permit the folds of curtains or the like to be attractively draped to the hanger, upon the supporting plate 11 and in proximity to the hook 12 is provided a hanging element or pin 27. The hanging 25 element or pin 27 may be curved upwardly, as indicated, so as to properly support the folds of the drapery when suspended thereon, or permit the drapery to be conveniently removed therefrom when it is desired to 30 entirely detach the drapery from the curtain hanger.

In the foregoing description I have embodied the preferred form of my invention, but I do not wish to be understood as limiting myself thereto, as I am aware that modifications may be made therein without departing from the principle or sacrificing any of the advantages of this invention, therefore I reserve to myself the right to make 40 such changes as fairly fall within the scope thereof.

Having thus described my invention, I claim as new and desire to secure by Letters Patent:—

45 1. A curtain hanger of the character described comprising in combination, a slotted hook member, adapted to be hooked to a curtain pole, a supporting member integrally formed with said hook member, and 50 provided with teeth at its lower end, a clamping member stamped out of the material of said supporting member, extending downwardly and parallel to said supporting member in front thereof having openings 55 in front of the teeth of said supporting

member, means for clamping a curtain or drapery between said supporting and clamping members, and auxiliary means for positively holding the folds of a curtain or drapery against displacement, substantially 60 as described.

2. A curtain hanger of the character described comprising in combination, a slotted hook member, adapted to be hooked to a curtain pole, a supporting member integrally formed with said hook member, and provided with teeth at its lower end, a clamping member stamped out of the material of said supporting member, extending downwardly and parallel to said supporting member in front thereof having openings in front of the teeth of said supporting member, lugs upon opposite sides of the supporting member having eyes, a lever provided with pins rotatably mounted 75 in the eyes of said lugs, a finger upon said lever for engaging in conjunction therewith said clamping member, and auxiliary means for positively holding the folds of a curtain or drapery against displacement, substantially 80 as described.

3. A curtain hanger of the character described comprising in combination, a slotted hook member, adapted to be hooked to a curtain pole a supporting member integrally 85 formed with said hook member, and provided with teeth at its lower end, a slotted clamping member stamped out of the material of said supporting member, extending downwardly and parallel to said supporting member in front thereof, having openings in front of the teeth of said supporting member, lugs upon opposite sides of the supporting member having eyes, a lever provided with pins rotatably mounted in 90 the eyes of said lugs, a finger upon said lever for engaging in conjunction with said lever said clamping member, and an auxiliary hook integrally formed with the supporting member, having a sharp upwardly disposed 95 point and being adapted to engage part of the curtain for positively holding the same in its folded form against displacement, substantially as described.

This specification signed and witnessed 100 this eleventh day of December A. D. 1911.

JOHN UMSTÄTTER.
